SIGNAL DEVICE

Filed Jan. 20, 1938

FIG. 1

UNITED STATES PATENT OFFICE

2,217,073

SIGNAL DEVICE

Herbert F. Obergfell, River Forest, Ill., assignor
to Associated Electric Laboratories, Inc., Chi-
cago, Ill., a corporation of Delaware

Application January 20, 1938, Serial No. 185,848

1 Claim. (Cl. 177—7)

The present invention relates to signal de-
vices, and more particularly to ringers for use
in telephone desk stands of the cradle type, or
the like.

- 5 It is an object of the present invention to
provide an improved signal device of compact
and rugged construction which may be readily
mounted directly within a telephone desk stand
of the cradle type.
- 10 Another object of the present invention is to
provide a signal device embodying an improved
gong arrangement which occupies a minimum
amount of space and which produces a pleasing
tone.
- 15 In brief, the objects set forth above are in
part realized in accordance with the present in-
vention by providing in a signal device a pair
of gongs arranged in nested relation in order to
conserve space and secured to a support by an
improved arrangement which accommodates ad-
justments of the positions of the gongs indi-
vidually with respect to an associated gong
striker. The gong striker is carried by a pivot-
ally mounted armature and is adapted to en-
gage the gongs alternately. The gong striker
is actuated into alternate engagements with the
gongs by an arrangement including a magnetic
core structure with which the pivotally mounted
armature is associated.
- 20 Further objects and advantages of the present
invention will become apparent as the following
description proceeds, and the features of novelty
which characterize the invention will be pointed
out with particularity in the claims annexed to
35 and forming a part of this specification.
- 25 For a better understanding of the present in-
vention, reference may be had to the accompan-
ying drawing, in which Fig. 1 is a front elevational
view of a ringer embodying the present invention;
30 Fig. 2 is a side elevational view of the ringer
shown in Fig. 1; Fig. 3 is an enlarged fragmentary
side elevational view, partly in section, of the
40 ringer taken along the line 3—3 of Fig. 1; and
Fig. 4 is an exploded view, partly in section, of
45 the mounting arrangement for the gong striker
shown in Fig. 3.

50 Referring now more particularly to Figs. 1, 2,
and 3 of the drawing, there is shown a signal de-
vice or ringer comprising a magnetic core struc-
ture 10, a pivotally mounted armature 11 asso-
ciated with the core structure 10, and a pair of
55 nested gongs 12 and 13 carried by a support 14.
The magnetic core structure 10 includes a sub-
stantially L-shaped permanent bar magnet 15
arranged adjacent a collar 16, a core member 17

extending through the collar 16, and a pair of
pole pieces 18 and 19 carried by the opposite ends
of the core member 17. The collar 16 is arranged
intermediate the ends of the core member 17
and is supported on a tubular sleeve 17a thereon.
In order to prevent the setting up of eddy cur-
rents in the collar 16 due to variations in the
magnetic flux passing through the core member
17 during the operation of the ringer, the collar
16 is slotted along its length as indicated at 16a.
The slot 16a interrupts the circuit of these eddy
currents in the collar 16 about the core member
17 which prevents these eddy currents from flow-
ing in the collar 16. Insulating washers 20 and
21 encircling the core member 17 are arranged
on opposite sides of the collar 16, and insulating
washers 22 and 23 encircling the core member
17 are arranged adjacent the pole pieces 18 and
19, respectively, in order to position a pair of
magnetizing windings, shown dotted, carried by
the core member 17. One of the windings is
adapted to surround the core member 17 between
the insulating washers 20 and 22, and the other
of the windings is adapted to surround the core
member 17 between the insulating washers 21 and
23. These magnetizing windings are so ar-
ranged that they produce accumulative magnetic
fluxes in the core member 17, when they are con-
nected in series across a suitable source of alter-
nating current supply.

30 As best shown in Figs. 3 and 4, the armature
supporting arrangement comprises a substan-
tially U-shaped bracket 24 secured to the lower
portion of the collar 16 and having a pair of
spaced apart arms 25 and 26. An opening 28 is
35 formed in the arm 25 adjacent the outer end
thereof, and a somewhat larger opening 29 is
formed in the arm 26 adjacent the outer end
thereof, these openings being arranged in align-
ment with each other in order to receive a pin
40 member 30 extending between the arms 25 and
26. One end of the pin member 30 is provided
with a knurled portion 31, which is adapted fric-
tionally to engage the inner surface of the open-
ing 28 formed in the arm 25 in order to retain
45 this end of the pin member 30 firmly in place.
The opposite end of the pin member 30 extends
through the opening 29 formed in the arm 26,
and is arranged in spaced relation to the sur-
rounding inner surface of this opening. The
50 inner surface of the opening 29 formed in the
arm 26 is threaded to receive an externally
threaded hollow bushing 32, which fills the inter-
vening space between the inner surface of the
opening 29 and the end of the pin member 30.

extending through the opening 29, this end of the pin member 30 being snugly accommodated in the opening formed in the hollow bushing 32. By forming the opening in the bushing 32 closely to conform to the exterior surface of the free end of the pin member 30, the hollow bushing 32 may be made closely to surround the free end of the pin member 30 which extends through the opening 29 formed in the arm 26 and firmly to retain this end of the pin member 30 in place. The hollow bushing 32 is provided with an enlarged head which is slotted as indicated at 33, in order to receive a screw driver or the like to facilitate placement and removal of the hollow bushing 32. A threaded locknut 34 is arranged on the threaded portion of the hollow bushing 32 in order to retain the hollow bushing 32 securely in place on the arm 26 of the bracket 24.

The armature supporting arrangement also includes a substantially U-shaped bracket 35 provided with a pair of spaced apart arms 36 and 37 having aligned openings 38 and 39, respectively, formed therein, which serve as bearings for pivotally supporting the bracket 35 on the pin member 30, the bracket 35 being retained in position on the pin member 30 by the inner end of the hollow bushing 32. The armature 11 is secured intermediate its ends to the bracket 35 by a pair of rivets 40. In order to prevent the ends of the armature 11 from sticking to the faces of the pole pieces 18 and 19 during the operation of the ringer, a shim 41 formed of non-magnetic material is clamped between the armature 11 and the bracket 35 and extends between the ends of the armature 11 and the faces of the pole pieces 18 and 19. The armature 11 is provided with an offset arm 42 which carries a striker 43 having a striking head 44 arranged between the gongs 12 and 13, and adapted to engage the gongs alternately. The end of the armature 11 arranged adjacent the pole piece 18 is biased toward the pole piece 18 by an arrangement including a spring 45 extending between the offset arm 42 provided on the armature 11 and a clip 46 secured to the support 14 by a screw 47, the screw 47 also serving to secure the support 14, the collar 16, the tubular sleeve 17a, the core member 17, and the bracket 24 in assembled relation.

As best shown in Fig. 3, the permanent bar magnet 15 is secured to the bracket 24 by an arrangement including a clip 48, the clip 48 being fastened to an enlarged portion of the arm 25 of the bracket 24 by a pair of screws 49. The collar 16, the core member 17, the pole pieces 18 and 19, and the armature 11 are all formed of magnetic material. One end of the permanent bar magnet 15 is arranged in contact with the collar 16, and the other end of the permanent bar magnet 15 is arranged in spaced relation and closely adjacent the armature 11. When the magnetizing windings carried by the core member 17 are not energized, the permanent bar magnet 15 establishes a magnetic field through the core structure 10 and the associated armature 11, which imparts to the respective ends of the armature 11 a predetermined polarity influence and to the pole pieces 18 and 19 the opposite polarity influence. The forces produced by these polarity influences tend to move the ends of the armature 11 toward the pole pieces 18 and 19. However, the end of the armature 11 arranged adjacent the pole piece 18 is biased toward the pole piece 18 by the biasing spring 45.

During the operation of the device and when the magnetizing windings surrounding the core

member 17 are energized from a suitable source of alternating current supply, an alternating magnetic field is set up through the core structure 10 and the associated armature 11 which, together with the magnetic field established by the permanent bar magnet 15 through the core structure 10 and the associated armature 11, causes the armature 11 to oscillate about its pivot provided by the pin member 30. The end of the armature 11 arranged adjacent the pole piece 19 against the bias of the spring 45 is moved toward the pole face of the pole piece during one-half of each cycle of the applied voltage, and the end of the armature 11 arranged adjacent the pole piece 18 is moved toward the pole face of this latter pole piece during the other half of each cycle of the applied voltage. Thus the ringer is of the polarized type, and the striking head 44 of the striker 43 is actuated into alternate striking engagements with the gongs 12 and 13.

In order to provide a distinctive composite tone, the gongs 12 and 13 are so constructed and arranged that they have different natural frequencies of vibration and individually produce different tones when they are struck by the striking head 44 of the striker 43. Thus the ringer is of the dual tone type and produces two distinct tones when it is operated, these tones blending to produce a particularly pleasing audible sound. Each of the gongs 12 and 13 is of substantially cup-shaped configuration and comprises an end wall provided with an opening therethrough which is eccentrically located with respect to the geometric center thereof. In Fig. 1, the centers of the openings provided through the gongs 12 and 13 are indicated at 50, the geometric center of the gong 12 is indicated at 51, and the geometric center of the gong 13 is indicated at 52. The gong 12 is secured to the support 14 by an arrangement including a threaded member 53 extending through the eccentrically located opening provided in the gong 12, the member 53 being arranged in threaded engagement with an internally threaded opening formed in the support 14 adjacent the upper end thereof. The threaded member 53 is provided with an enlarged hollow head 54 which is internally threaded to receive a threaded member 55 extending through the eccentrically located opening provided in the gong 13. Thus the threaded members 53 and 55 provide a common arrangement for securing the gongs 12 and 13 to the support 14 and in spaced-apart relationship with respect to each other, the gong 12 being directly secured to the support 14 by the threaded member 53, and the gong 13 being directly secured to the enlarged head 54 of the threaded member 53. This common arrangement also accommodates adjustments of the positions of the gongs 12 and 13 individually with respect to the striking head 44 of the striker 43.

In order to adjust the position of the gong 12 with respect to the striking head 44 of the striker 43, the threaded member 53 is loosened and the gong 12 is rotated about the threaded member 53. Due to the eccentric location of the opening provided in the gong 12 with respect to its geometric center 51 this rotation causes the struck surface of the gong 12 to be moved toward or away from the striking head 44 of the striker 43. After the gong 12 has been rotated to the desired adjusted position, the threaded member 53 is tightened to retain the gong 12 securely in place. In order to adjust the position of the gong 13 with respect to the striking head 44 of the striker 43, the threaded member 55 is loosened

and the gong 13 is rotated about the threaded member 55. Here again, the eccentric location of the opening provided in the gong 13 with respect to its geometric center 52 causes the struck 5 surface of the gong 13 to be moved toward or away from the striking head 44 of the striker 43. After the gong 13 has been rotated to the desired adjusted position, the threaded member 55 is tightened to retain the gong 13 securely in place.

10 From the foregoing description it is apparent that a signal device or ringer is provided which is of rugged construction and comprises a minimum number of parts. Moreover, the ringer occupies a minimum amount of space, due to the nested 15 relation of the gongs embodied therein, which permits the ringer to be mounted directly within a telephone desk stand of the cradle type.

While a particular embodiment of the present invention has been shown, it is not desired that 20 the invention be limited to the particular construction shown and described, and it is intended in the appended claim to cover all modifications within the spirit and scope of the present invention.

25 I claim:

A signal device comprising inner and outer gongs arranged in spaced-apart and nested relationship, each of said gongs being substantially cup-shaped and having an end wall provided with

an eccentrically located opening therein, a support arranged exteriorly of said outer gong and adjacent the end wall thereof, means including a first member extending through the opening in the end wall of said outer gong and threaded into an opening provided in said support for securing the end wall of said outer gong to said support, means including a second member extending through the opening in the end wall of said inner gong and threaded into an opening 10 provided in said first member for securing the end wall of said inner gong to said first member, means including a head carried by said first member and disposed between the end walls of said gongs for retaining said gongs in spaced- 15 apart nested relationship, a striker having a striking head arranged between said gongs in striking relationship therewith, said outer gong being rotatable about said first member to accommodate adjustment of the position thereof with 20 respect to the striking head of said striker, said inner gong being rotatable about said second member to accommodate adjustment of the position thereof with respect to the striking head of said striker, and means for actuating the striking head of said striker into alternate striking engagements with said gongs. 25

HERBERT F. OBERGFELL.
